UNITED STATES PATENT OFFICE.

JAMES H. KELLY AND CHARLES H. BROAD, OF ROCHESTER, NEW YORK;
SAID BROAD ASSIGNOR TO SAID KELLY.

DEVICE FOR BENDING TUBES.

SPECIFICATION forming part of Letters Patent No. 369,011, dated August 30, 1887.

Application filed February 10, 1887. Serial No. 227,204. (No model.).

To all whom it may concern:

Be it known that we, JAMES H. KELLY and CHARLES H. BROAD, both citizens of the United States, residing at the city of Rochester, in the 5 county of Monroe and State of New York, have invented a certain new and useful Improvement in Apparatus for Bending Tubes and Pipes; and we do hereby declare that the following is a full, clear, and exact description of the same, reference being had to the drawings accompanying this application.

Our improvement relates to means for bending tubes and pipes by placing the same on a grooved forming head or bed of the shape to 15 which it is desired to have the tube conform when bent, inserting a rod into the end of the tube, and then sweeping a die over the forming-head, said rod being carried around the forming-head, thereby producing the bend in the 20 tube.

The invention consists, essentially, of a form to which the tube is clamped, a rod or mandrel which enters the tube and by which the tube is bent, and a carrier to which the rod is attached; also, of other parts, which will be more 25 fully described.

In the drawings, Figure 1 is a plan view of the machine. Fig. 2 is a side elevation of the same. Fig. 3 is a central longitudinal vertical section. 30 Fig. 4 is a front elevation of the grooved forming-head, the yoke, the grooved die, and connecting parts. Fig. 5 is a diagram showing a piece of tube with the rod therein, and illustrating the method of bending the tube.

A indicates a bed, and A' a circular head forming a continuation of same, said bed and forming-head being provided with a half-circular groove, a, in which the tube is laid to be bent.

B is a clamp resting over the bed, said clamp also having a half-circular groove in its under side. Said clamp is forced down to clamp the tube by any suitable means.

C is a yoke, having straps or bearings b b, 45 resting and turning on journals c c of the forming-head A', as shown most clearly in Fig. 4. These straps may either be made separate and attached by screws d d or other means to the sides of the yoke, or they may be made an integral part of the yoke itself. This yoke is

provided with a handle, f, by which it is operated.

D is a lever forming the die, the same being pivoted at g in a fork of the yoke, so as to have an independent turning movement therein. It 55 is provided at the top with a handle, h, by which it is operated. Its lower end reaches to the surface of the circular head A', and it is provided at the bottom with a half-circular groove, a', which embraces the upper surface of the 60 tube. The yoke C and die D sweep around the forming-head, as indicated by the full and dotted lines, Fig. 3, and are accessory to the bending of the tube by the rod, as hereinafter described. The yoke and the die can be made in 65 one piece and be operative, but are preferably made separate to facilitate the insertion and removal of the tube.

E is a rod which is inserted in the end of the tube, the inner end being carried to the proper 70 position between the forming-head A' and the grooved die D, as shown in Fig. 3. The outer end of the rod rests in a stirrup, G, that is attached at i i to the sides of the yoke, by which means it is carried around with the yoke and 75 die. The rod is held to the stirrup by any desired means, that shown in the drawings being a nut, k, which screws up on a thread on the rod, and thus serves as a gage to adjust the rod forward or back, to fit it properly between the 80 forming-head and die. Any other suitable gage may be used for the purpose.

We do not confine ourselves to the construction of the stirrup as described, as any other attachment that will carry the rod as fast as 85 the die moves around the forming-head or the tube is bent will suffice.

The operation is as follows: The tube is laid in the groove a and clamped in place, and the die D is turned down, so as to embrace it. The 90 rod E is inserted in the outer end of the tube, so as to bring the inner end of the rod in proper position between the forming-head and die. The yoke C and die D are then turned around the forming-head, as indicated by the dotted 95 lines in Figs. 2 and 3. The inner end of the rod is drawn along inside the tube as fast as the die sweeps around the outside of the tube, and this rod acts as a bender of the tube, and the end of it as a core to prevent the collapse of 100

the tube. The result is a perfect bend without crushing the tube. The under part of the tube where the bend is made can be upset, crimped, or corrugated as the tube bends, doing the said crimping or corrugating at the same time with the bending, or the tube, when bent, can be left smooth its entire length. Tubes bent by this process are a new article of manufacture, and the article and process will form subjects-matter for other applications for patent.

It is not absolutely necessary to the practical working of this invention that a swinging yoke and die be used; but the work can be done by the rod inserted in the tube and properly held and made to sweep around the forming-head coincident with the bending of the tube, as described.

A plain straight rod will do the work practically and well; but to facilitate the operation, the rod is preferably made with an enlarged head at the inner end, where the bending takes place.

Having described our invention, what we claim as new, and desire to secure by Letters Patent, is—

1. In an apparatus for bending tubes and pipes, the combination of a form on which the tube is laid, a clamp for holding the tube, a rod or mandrel for bending the tube, and a carrier for holding the rod, as specified.

2. In an apparatus for bending tubes and pipes, the combination of a form on which the tube is laid, a clamp for holding the tube, a rod or mandrel for bending the tube, a carrier for holding the rod, and a die which sweeps around the form, as set forth.

3. The combination of a form on which the tube is laid, a clamp for holding the tube, a rod or mandrel for bending the tube, a carrier for holding the rod, a die which sweeps around the form, and a yoke to which the die is attached, as specified.

4. The combination of a form, a clamp, a rod or mandrel, a die, a yoke, and a stirrup attached to the yoke, said stirrup serving as a holder for the rod, as specified.

5. In an apparatus for bending tubes and pipes, the combination, with a form, to which the tube is clamped, of a rod or mandrel attached to a carrier, said rod or mandrel entering the end of the tube and producing the bend by being drawn around the form, as set forth.

In witness whereof we have hereunto signed our names in the presence of two subscribing witnesses.

JAMES H. KELLY.
CHAS. H. BROAD.
